Primary Examiner — George D. Kirschbaum*Assistant Examiner* — Patricia K. Beard(57) **CLAIM**

The ornamental design for a basketball hoop, as shown and described.

DESCRIPTION

FIG. 1 is a perspective view of a basketball hoop showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is a perspective view of the basketball hoop as it would be positioned during use; and,

FIG. 10 is an enlarged view of the encircled portion in FIG.

9.

The dash-dot-dash lines in FIG. 9 and FIG. 10 illustrate the enlarged view indicators and form no part of the claimed design.

The broken lines of FIGS. 9 and 10 depicting a portable basketball hoop represent environmental structure that forms no part of the claimed design. The remainder of the broken lines depict portions of the basketball hoop that form no part of the claimed design.

1 Claim, 10 Drawing Sheets(56)
